UNITED STATES PATENT OFFICE

GIDEON SUNBACK, OF MEADVILLE, PENNSYLVANIA, ASSIGNOR TO HOOKLESS FASTENER COMPANY, OF MEADVILLE, PENNSYLVANIA, A CORPORATION OF PENNSYLVANIA

SEPARABLE FASTENER

Application filed February 11, 1925, Serial No. 8,340. Renewed December 14, 1932.

This invention relates to separable fasteners of the slider controlled type and has for its object to provide such a device which has increased lateral flexibility together with the ability to compensate for a variation in length of fabric stringers to which the interlocking members are attached, yet is secure, strong, and capable of being cheaply made in quantity production.

The fastener shown in my Patent No. 1,219,881, dated March 20, 1917 embodies continuous fabric stringers carrying interlocking members alike on each stringer, but in alternating or staggered arrangement, whereby interlocking is effected by the engagement of each member on one stringer with two members on the other stringer. As specially worked out in that patent, such fastener has a very considerable lateral flexibility, but little or no accommodation to variation in stringer length owing to the close alternating engagement of the several members. It is known that continuous fabric stringers fluctuate considerably in length owing to humidity conditions, a stringer when wet being appreciably longer than when dry. Hence, when drying, the longitudinal contraction causes the alternately interlocked stringers to wave or curl up out of the interlocking plane, which, while not impairing the security of the fastener, is objectionable in appearance on various articles, particularly on rubber footwear which is subjected to extremes of moisture conditions. This tendency to wave or curl is especially noticeable in footwear because the fastener is usually closed under strain in view of the desirability of securing a good fit, so that the only way the contraction of the stringers can be accommodated is by displacement of the interlocking members out of the interlocking plane.

According to this invention, I have solved the problem of providing the locking members arranged opposite one another along a pair of flexible fabric stringers with any desired spacing between the members along the same stringer. Preferably, each member is provided with a projection and recess on its longitudinal edge whereby the lock-

ing is doubly secure. To facilitate the engagement of the projection with the recess, one or more additional guiding surfaces on the projection are provided.

In the accompanying drawings: Figure 55 1 shows a fastener embodying this invention,

Fig. 2 is a preferred form of fastener, Fig. 3 is an enlarged view of the locking members of Fig. 1,

Fig. 4 is a section on the line 4a—4a of Fig. 1,

Fig. 5 is an enlarged perspective of one of the locking members shown in Fig. 2,

Fig. 6 is an enlarged perspective of one of the locking members shown in Fig. 1,

Fig. 7 is a modified form of fastener embodying this invention,

Fig. 8 illustrates the fastener of Fig. 1 with the locking members widely spaced on 70 the stringers,

Fig. 9 is an enlarged perspective of the fastener member of Fig. 7 having a projection,

Fig. 10 is an enlarged perspective of the fastener member of Fig. 7 having a recess,

Fig. 11 is a section on the line 11a—11a of Fig. 7,

Fig. 12 shows another form of this invention.

In Fig. 1, the flexible stringers 30 are provided with cords 31 secured along their longitudinal edges and around which are clamped the locking members 32 by means of the compressible jaws 35. Each of these locking members shown in detail in Figs. 3 and 6 is provided with a projection 33, and also has a recess 34 preferably coextensive with the projection and in the same transverse plane as the projection for engagement by the projection of the opposite locking member. Each projection 33 is provided with guiding surfaces 36 and 37, respectively, above and below its tip or outer end and below these guiding surfaces is a hook shaped portion 38 which engages the lower wall or edge 39 of the recess in the opposite locking member. The upper inner edge 40 of the recess 34 prevents the opposite projection 33 from being withdrawn 100

laterally from the recess 34 when it is raised longitudinally inside the recess. The top and bottom portions 41 of the locking members project as far as indicated at 42 in dotted lines of Fig. 3 so that the clamping jaws are of less width at the top and bottom than are the corded edges 31, whereby, when the corded edges are enclosed by the clamping jaws and the inturned ends 43 of the jaws, said corded edges are compressed in all directions with the result that the locking member is securely fastened on the corded edge and does not slip out of place. This member may be formed in any suitable manner, as by stamping the projection 33, recess 34, clamping jaws 35, and edges 42 out of a flat strip of metal in a single operation, then bending the jaws 35 to U-shape and turning in the edges 43 of the jaws, turning in the edges 42, and bending up the projection 33 to lie in a plane parallel with the jaws 35, as shown in Fig. 6. A slider 44 having diverging channels 45 controls the engagement and disengagement of said locking members 32.

The preferred form illustrated in Figs. 2 and 5 is the same as that in Fig. 1 since each locking member has both a projection 46 and a recess 48 but differs in having the pairs of clamping jaws 47 spaced apart and joined by the bridge 49 containing the recess and projection. This member may be formed of flat strip material bent double to substantially U-shape, with the recess 48 punched out of the material between the bends and the flat projection 46 formed to lie in a plane normal to the stringer.

In Fig. 7 is shown a modified construction in which the locking members 50 on one stringer constitute the projections while those on the opposite stringer are provided with a recess. Each of the projection locking members 50 is provided with guiding surfaces 56 and 57 above and below its tip for the same purpose as before, namely, to facilitate engagement between the projection and recess and to help raise or lower one member if it is slightly out of line or at a different height. The guiding surface below the tip, or widest part of the recess, also functions as a means to facilitate entry of the projection into the slider. Beneath the guiding surfaces 56 and 57 a recess forms a catch or hook portion 58 for retaining the projection within the recess 55 of the opposite member 51. This opposite member 51 is also provided with spaced prongs 54 which pass into the corded edge and bend over at 59 to retain the locking members in place. As shown in Fig. 11, the edge of the stringers 61, comprises an enlarged cord 60 through which the stapled locking members are passed and their ends bent over. The flexible stringer material 61 is then, or previously, passed around to

completely enclose the cord 60, and stitches 62 may retain the material and cord tightly held together. With this form of invention much of the metal parts are covered and the slider moves on a nonmetallic track formed by the flexible stringer material surrounding the corded edge.

Fig. 12 illustrates a locking member of the same general type as shown in Figs. 1 to 6, but in which the projection 82 is stamped and bent from the material of the tubular member, and the recess 83 is constituted by the perforation left from stamping up the integral projection.

Among the advantages of this invention may be mentioned increased flexibility of the fastener both laterally and longitudinally. Since the locking members are located opposite each other their separation along the stringers may give great lateral flexibility without causing the members to come unfastened. This spacing of the pairs of oppositely located locking members also permits contraction and expansion of the stringer material such as occurs when the

fastener is used on washable goods, for example, which get wet and shrink on drying. Then again when used on a shoe, for instance, the longitudinal spacing of the pairs of locking members enables considerable give to occur in the fastener with the natural movement of the foot in walking without having locking members buckle or the fastener feel unduly stiff.

The provision of at least two guiding surfaces facilitates entry of the projections within the recesses of opposite locking members. This provision of a guiding surface below the tip of the projection not only distinguishes from previous fasteners of this general type but also serves the purpose of facilitating entry of the projection member into the slider channels since if the projection is slightly twisted from its normal plane, this lower guiding surface engaging the top of the slider channel causes the locking member to be moved into its proper position.

Another advantage is that the little hook portion below the guiding surface is close to the locking member and stringer instead of being near the tip or outer part of the projection where it might catch on the top of the slider channels. The locking members of Figs. 1 to 6 and 12 are doubly secure in locking because each is provided with a projection and recess. As shown in Figs. 5 and 6, these locking members may be made relatively thin so as not to take up any considerable space, in fact, they are about the same dimensions as the corded edge of the stringers in Figs. 1 to 6, while in Figs. 7 to 11 it will be seen that the locking members are of less thickness than the corded stringer edge. Because of the locking members shown in Figs. 1 to 6 being

- doubly secure in locking and because the locking members are all alike, this embodiment is preferable from a manufacturer's standpoint for quantity production. Increasing the spacing between the pairs of opposite locking members not only increases flexibility but decreases the cost as a minimum number of locking members per unit length may be used. An advantage of the locking member shown in Fig. 12 is that it is integral and may be made in one piece of sheet metal, stamped and bent to form, more readily than some of the previously described locking members. The preferred form shown in Figs. 2 and 5 may also be made in one piece by cutting a strip of material having an L-shape cross section so that the projection 46 is stamped from one side and the recess 48 and pairs of jaws 47 both stamped from the other side of the strip, said jaw portions then being bent back substantially at right angle to the bridging portion 49, as illustrated in the drawings.
- Another advantage of the locking members illustrated in Figs. 1-6 and 22, is that this type can be made cheaper than the other forms illustrated because dies and tools can be used longer since greater clearances are permissible. In this type of fastener, the recess can be much larger since raising one projection also raises the lower edge of one recess and therefore will not allow accidental disengagement of this form of fastener as readily as the other forms of fastener if they had the same amount of movement to the projection member. This is because the projection of one locking member engages at a bottom edge of the recess of the opposite locking member whether moved up or down, as moving one locking member up is equivalent to moving the opposite locking member downward and results in engagement between a projection and lower edge of an opposite recess. Also with this form of fastener, two guiding surfaces 36 and 37 are not necessary on each projection, but the fastener may be satisfactorily operated if only one surface on each projection, namely the guiding surface 37, be present. The clearance between the top of a projection and the top of a recess may be any amount, the only necessary limitation for this preferred type of fastener with a projection and recess on each locking member being that the bottom of the hook portion 38 must be below the bottom of the recess in each member in order for the fastener to be securely closed.
- I claim:
1. A fastener comprising a pair of flexible stringers, locking members secured to each of said stringers substantially opposite one another, each of said members having a projection and recess on its longitudinal edge for engagement with a corresponding recess and projection on the opposite member of the opposite stringer, said projection being provided with guiding surfaces one of which is shaped to facilitate engagement with the recess when the projection is above and the other of which is shaped to facilitate engagement with the recess when the projection is below said recess. 70
  2. A fastener comprising a pair of flexible stringers, locking members secured to said stringers substantially opposite one another, a projection and recess on the longitudinal edge of each member for engagement with a corresponding recess and projection on the opposite locking member of the other stringer, each projection having a guiding surface sloping outwardly to raise it into engagement with its cooperating recess. 75
  3. A fastener comprising a pair of flexible stringers each having thereon similar locking members arranged for edgewise engagement and each locking member having a projection and a recess coextensive therewith on its longitudinal edge adjacent the other stringer. 80
  4. A fastener comprising a pair of flexible stringers, locking members secured to each of said stringers substantially opposite one another, each of said members comprising a projection and recess on its longitudinal edge for engagement with a corresponding recess and projection on the opposite member of the other stringer, and a slider controlling said members. 85
  5. A fastener comprising a pair of flexible stringers, locking members secured to each of the stringers substantially opposite one another, each of said members comprising a recess and projection on its longitudinal edge located in the same transverse plane for engagement with a corresponding recess and projection in the opposite locking member, and a slider for controlling said members. 90
  6. A fastener comprising a pair of flexible stringers, locking members secured to each of the stringers substantially opposite one another, each of the members on both stringers being provided with a projection and recess on its longitudinal edge for engagement with the complementary parts of the opposite member, and a slider for controlling said members, each projection having guiding surfaces on each side of its tip, and a hook below said aforementioned guiding surfaces. 105
  7. A fastener comprising a pair of flexible stringers, locking members secured to each of said stringers substantially opposite one another, each of said members having a projection and recess on its longitudinal edge for cooperation with complementary parts on the longitudinal edge of the opposite member, said locking members being 110
  8. A fastener comprising a pair of flexible stringers, locking members secured to each of said stringers substantially opposite one another, each of said members having a projection and recess on its longitudinal edge for engagement with the complementary parts of the opposite member, said locking members being 115
  9. A fastener comprising a pair of flexible stringers, locking members secured to each of said stringers substantially opposite one another, each of said members having a projection and recess on its longitudinal edge for engagement with the complementary parts of the opposite member, said locking members being 120
  10. A fastener comprising a pair of flexible stringers, locking members secured to each of said stringers substantially opposite one another, each of said members having a projection and recess on its longitudinal edge for engagement with the complementary parts of the opposite member, said locking members being 125
  11. A fastener comprising a pair of flexible stringers, locking members secured to each of said stringers substantially opposite one another, each of said members having a projection and recess on its longitudinal edge for engagement with the complementary parts of the opposite member, said locking members being 130

- of integral strip metal and the projections being stamped therefrom.
8. A fastener comprising a pair of flexible stringers, locking members secured to each 5 of said stringers substantially opposite one another, a projection and recess on the longitudinal edge of each member for engagement with a cooperating recess and projection on the opposite member of the other stringer, 10 each projection having a tip, and guiding surfaces extending in opposite longitudinal directions on each side of said tip to raise or lower it into engagement with its cooperating recess.
- 15 9. A fastener comprising a pair of flexible stringers, locking members on one stringer each having a hooked projection, locking members on the opposite stringer each being provided with a recess to receive the projection on each of the first locking members, 20 and means on each recess member comprising another projection in the same transverse plane as the recess arranged to limit movement of the first projection therein.
- 25 10. A fastener comprising a pair of flexible stringers, locking members secured to each stringer, each being provided with a longitudinal edgewise recess and projection in the same transverse planes shaped to engage 30 the projection and recess of a cooperating member on the opposite stringer and shaped to maintain engagement regardless of the length of the recess.
11. A fastener comprising a pair of flexible 35 stringers, similar locking members substantially opposite one another on each stringer provided with a longitudinal edgewise recess and hooked projection, the hook portion of each projection being so shaped and located 40 as to maintain the engagement of said locking members on opposite stringers independently of the length of the recess.
12. A locking member comprising means for securing the same to a tape and having 45 a recess on its longitudinal edge, a projection on the same edge, a hook portion on said projection intermediate its lateral extremities, and a guiding surface between said hook portion and the outer end of said projection.
- 50 13. A locking member having means for securing the same to a tape, a recess and projection in the same transverse plane on the outer edge of said member, the bottom of the projection being located above the bottom 55 of the recess, and the projection being provided with a hook extending below the bottom of the recess.
14. A fastener comprising a pair of flexible stringers, locking members secured to 60 each of said stringers substantially opposite one another, each of said members having a projection and recess on its longitudinal edge for cooperation with the recess and projection of the opposite member, said locking 65 member being of integral strip metal, the projection being stamped therefrom and the recess being laterally of the projection.
15. A locking member for a slide type fastener comprising means for attaching same to a flexible material, a projection on its longitudinal edge for engagement with the recess in an opposite member, the longitudinal edge of said locking member also being provided with a recess adjacent said projection to receive the projection of said opposite member, a hook portion adjacent one end of the projection and at least one guiding surface on said projection extending outwardly from adjacent the hook portion. 70 75
16. A locking member for a slide type fastener comprising means for attaching same to a flexible material, a projection on its longitudinal edge for engagement with the recess in an opposite member, said locking member being provided with a recess in its longitudinal edge adjacent said projection to receive the projection of said opposite member, a hook portion adjacent an end of said projection, the end of said hook portion extending longitudinally at least beyond the 80 adjacent edge of said recess. 85
17. A fastener comprising a pair of flexible stringers, locking members secured to each of the stringers substantially opposite one another, and a projection and recess on the longitudinal edge of each of said members so arranged that the projections and recesses of each pair of opposite locking members will engage each other in substantially the same transverse plane. 90 95 100
18. A locking member for a slide type fastener comprising strip material bent double to substantially U-shape and formed adjacent its ends to provide clamping jaws, the material between the bends having a recess and a projection substantially transverse to said recess whereby said recess and projection may cooperate with complementary parts of a similar locking member. 105
19. A fastener comprising a pair of flexible stringers, locking members secured to each of said stringers substantially opposite one another, each of said members being provided with a projection and a recess on its longitudinal edge for cooperation with the recess and projection of the opposite locking members, and at least some of said members being provided with hook-shaped portions to retain the projections in said recesses. 110 115 120
20. A separable fastener comprising a pair of flexible stringers having a plurality of pairs of opposed locking members, each member of a pair having a recess facing the opposite stringer and a flat hook projecting in a plane normal to the stringer for engagement with the recess of the other member of said pair. 125
21. A locking member for a slide type fastener comprising spaced pairs of clamp- 130

ing jaws for securing same to a stringer, and a projection and recess in substantially the same transverse plane on the longitudinal edge of said member for engagement with a corresponding recess and projection of an opposite locking member.

22. A fastener comprising a pair of flexible stringers each having thereon similar

locking members arranged for edgewise engagement, each locking member having a projection and a recess on its longitudinal edge adjacent the other stringer, said recess extending in a longitudinal direction in an amount substantially equal to the width of the projection.
